UNITED STATES PATENT OFFICE.

JOHN A. FIELDS, OF SELDOVIA, TERRITORY OF ALASKA.

HANDLE FOR CANS.

Application filed January 20, 1928. Serial No. 248,247.

This invention relates to bales or handles adapted for use upon receptacles or containers.

An object of the invention comprehends 5 means for holding the handle flush against the receptacle to facilitate shipping and storing of the receptacle within the approximate area occupied by the receptacle per se.

Another object of the invention contemplates 10 locking means adapted for detachable engagement with one end of the handle to prevent displacement thereof when the same is called into use.

More specifically stated the handle member 15 is adapted to be bent upon itself within the locking element precedent to carrying the receptacle.

With the above and other objects in view, the invention further consists of the following 20 novel features, and details of construction, to be hereinafter more fully described, illustrated in the accompanying drawing and pointed out in the appended claims.

25 In the drawing:

Figure 1 is a perspective of a receptacle with the invention applied.

Figure 2 is a fragmentary elevation of a receptacle with the invention applied and 30 disposed in its initial position.

Figure 3 is a similar view with one end of the handle member bent upon itself within the locking element when the device is called into use.

35 Figure 4 is a sectional view taken through a receptacle and disclosing the disposition of the handle member in side elevation at right angles to Figure 2.

Figure 5 is a side elevation of the invention taken at right angles to Figure 3.

Figure 6 is a perspective of the locking element.

Figure 7 is a perspective view of the handle member per se.

45 Referring to the drawing in detail, wherein like characters of reference denote corresponding parts, the reference character 10 indicates a receptacle.

The invention embodies a handle member 50 adapted to be carried by a receptacle and to be flattened against one side thereof when stored and shipped but which is adapted to be extended to occupy the position as best

illustrated in Figure 5 of the drawing when the latter is called into use.

In carrying out the invention, I provide 55 an elongated flexible strip 11 soldered or otherwise secured as indicated at 12 upon the outer side of the receptacle.

A locking element in the nature of a plate 60 member 13 carried upon the receptacle 10 is provided with an elongated slotted portion 14 adapted to receive the free end of the strip 11 therethrough. That portion of the plate member 13 having the elongated slot 65 14 is outwardly flared as indicated at 15 from the adjacent wall of the receptacle as illustrated in Figure 4 of the drawing.

When the device is called into use, the strip 11 is pulled away from the adjacent 70 wall of the receptacle to occupy the position as best illustrated in Figure 5 of the drawing, and the free end thereof is bent upon itself within the elongated slot 14 in the plate member 13 and over and upon the 75 flared portion 15 thereof. The receptacle may then be immediately manipulated to discharge or dispense the contents thereof.

For purposes of convenience in the manipulation of a receptacle in conjunction 80 with the present invention, I have provided a handle portion 16 for the strip 11 and having inwardly turned edges 17 upon the side edges of the strip 11 to prevent the hands from becoming cut.

85 It is noted, from the nature of the invention, that the same may be applied upon the various forms, designs or types of receptacles and the presence thereof will in no way restrict the packing or shipping of receptacles equipped with the particular type of handle.

The invention is susceptible of various 90 changes in its form, proportions and minor details of construction, and the right is 95 herein reserved to make such changes as properly fall within the scope of the appended claims.

Having described the invention, what is claimed is:

100 1. In a handle, a flexible strip adapted to have one of its ends permanently attached to an article, a slotted plate adapted to be attached to said article to freely receive the opposite end of the strip, whereby the strip 105 may lie flat against the article or be ex-

tended with the free end of said strip shaped to provide a hook to engage the plate and form a handle.

2. In a handle, a flexible strip adapted to have one of its ends permanently attached to an article, a slotted plate adapted to be attached to said article to freely receive the opposite end of the strip, whereby the strip may lie flat against the article or be extended with

the free end of said strip shaped to provide a hook to engage the plate and form a handle, and a relatively long reinforced portion intermediate the ends of the strip to provide a gripping portion and assist in shaping the handle when the latter is extended. 10 15

In testimony whereof I affix my signature.

JOHN A. FIELDS.
